UNITED STATES PATENT OFFICE.

SAMUEL T. WILLIAMS, OF TROY, NEW YORK, ASSIGNOR OF ONE-HALF TO
ROBERT W. HUNT, OF SAME PLACE.

ROLLING-MILL.

SPECIFICATION forming part of Letters Patent No. 284,700, dated September 11, 1883.

Application filed December 27, 1882. (No model.)

To all whom it may concern:

Be it known that I, SAMUEL T. WILLIAMS, of Troy, in the county of Rensselaer and State of New York, have invented certain new and 5 useful Improvements in Rolling-Mills; and I do hereby declare the following to be a full, clear, and exact description of the invention, such as will enable others skilled in the art to which it pertains to make and use the same.

10 My invention relates to an improvement in mills for rolling railroad-rails, bars, plates, and all masses of metal of similar shape.

Rolling-mills as heretofore constructed may be classified under three heads: first, those 15 having two rolls rotating in the same direction; second, those having three rolls, the upper and lower rolls being rotated in opposite directions; and, third, those having two rolls arranged to be reversed in the direction of 20 their rotation between the successive passes of the article being rolled. Mills of the first class are objectionable on account of the great expenditure of time and labor involved in idly returning the article being rolled from the 25 delivery to the entering side of the rolls. On the other hand, mills of the second class are objectionable on account of the expenditure of time and labor necessarily attendant upon raising and lowering the article being rolled to 30 enter it between the upper and lower rolls, while mills of the third class are objectionable on account of the time involved in reversing the rolls between the successive passes of the article being rolled, and also on account of the 35 great wear on the rolls and their associated mechanism which the reversing entails.

My invention comprehends the construction 40 of a rolling-mill of the character designated which shall obviate the objections incident to these classes of mills, above referred to, and which shall combine simplicity and cheapness of construction with durability and efficiency in use.

With these ends in view my invention consists in certain details of construction and combinations of parts, as will be hereinafter described, and pointed out in the claims.

45 The accompanying drawing represents a plan view of a rolling-mill embodying my invention.

A and B respectively represent the upper rolls of two sets of rolls placed end to end and independently rotated in opposite directions, as indicated by arrows on the fly-wheel C, by power applied through the pinions D.

55

A table, E, to be hereinafter designated as the "entering-table," and consisting of a series of rollers, F, mounted in suitable frame-work, is located in front of the entering side of the rolls A, several or all of the rollers F being rotated in the direction of the said rolls by power communicated to them through a shaft, G, provided with gears H, arranged to mesh with similar gears, I, attached to the rollers.

60

A table, E', to be hereinafter designated as the "delivery-table," and similar in construction to the entering-table E, is located in front of the delivery side of the rolls A, and adapted to receive the article being rolled as it is delivered from them. No provision is shown for 65 rotating the rollers F' of this table; but this may be provided for, if found desirable. Cylinders J, operating from the outer edge of and at right angles with the said delivery-table, are provided with suitable water or steam connections, (not herein shown,) according to the motor employed in actuating them. The outer ends of the piston-rods K of the said cylinders are adapted to engage with the articles delivered onto the table E', and move them trans-

70

versely over it and onto the entering-table L of the rolls B, which, as before described, rotate in reverse direction from the rolls A. The said entering-table L, which is substantially the same in construction as the tables E 75 and E', is parallel with and located in or about the same horizontal plane as the latter. The rollers M of this table are rotated in the direction of the rolls B by power transmitted to them through the shaft N, provided with gears O, and meshing with similar gears, P, attached to the rollers. The articles being rolled are delivered from the rolls B onto the delivery-table L', the same being substantially the same 80 in construction as the tables already described, and parallel with and located in or about the same plane as the entering-table E of the rolls A. Cylinders J', operating from the outer edge of and at right angles with the said delivery-table L', are connected with suitable

95

100

steam or water mains, (not herein shown,) according to the motor employed in actuating them. The outer ends of the piston-rods K are adapted to be engaged with the articles delivered onto the table L' by the rolls B and move them transversely over and onto the entering-table E of the rolls A. A few of the outer rollers, M', of the said table L' are rotated in the direction of the rolls B by the shaft N, provided with gears O', which mesh with similar gears, P', mounted on the ends of the rollers. If desired, similar provision may be made for rotating the rollers F' of the delivery-table E'.

15 In virtue of the within-described arrangement of rolls, tables, and the devices for moving the article being rolled, the transit of the two sets of rolls is made very rapidly and with comparatively little manual intervention, the article being reduced being passed through each set of rolls once in every uninterrupted circuit of the tables. While it is apparent that the article to be rolled may be started from either of the entering-tables, let it be assumed, for the purpose of illustration, that it is started from the entering-table E of the rolls A, through which it passes, being delivered onto the delivery-table E', from which it is immediately transferred to the entering-table L of the rolls B by the piston-rods K. From the said table L it is passed through the rolls B and delivered onto the delivery-table L', from which it is transferred by the piston-rods K to the table E, from which it first started, the article being continued in the circuit of the tables, as described, until it is reduced to the desired form. Of course it is not necessary to pass the article being rolled successively through the two sets of rolls, for it may be returned idly over and repassed through either set of rolls as many times as need be.

45 In the improved mill herein described the wear of the mechanism, the time elapsing between the successive passes, and the labor of manipulation are reduced to the minimum, whereby all operations under it are cheapened and facilitated. While the arrangement of placing the rolls of the two sets end to end is probably more practical than any other, they 50 may be placed at any angle desired. Again, the invention is not limited to the devices shown for transferring the article being rolled from the delivery to the entering tables of the respective sets of rolls, for any other suitable 55 devices may be employed instead. Nor is the invention restricted to the particular con-

struction of rolls, tables, and associated mechanism herein set forth. I would therefore have it understood that I do not limit myself to the construction and combination of 60 parts herein shown and described, but hold myself at liberty to make such slight changes and alterations as fairly fall within the spirit and scope of my invention.

Having fully described my invention, what 65 I claim as new, and desire to secure by Letters Patent, is—

1. An improved rolling-mill, consisting of two sets of rolls arranged to rotate in opposite directions, of stationary entering and delivery tables for each set of rolls, and of means for transferring the article being rolled transversely over the delivery-tables, and onto the entering-tables adjoining them, substantially as set forth. 70

2. An improved rolling-mill, consisting of two sets of rolls arranged to rotate in opposite directions, of stationary entering and delivery tables for each set of rolls, and of transferring devices operating from the outer edges 80 of the delivery-tables, and arranged to transfer the article being rolled transversely over them and onto the adjoining entering-tables, substantially as set forth.

3. An improved rolling-mill, consisting of 85 two sets of rolls arranged to rotate in opposite directions, of stationary entering and delivery tables for each set of rolls, and of pistons operating from the outer edges of the delivery-tables, and arranged to transfer the article being rolled transversely over them and onto the adjoining entering-tables, substantially as set forth. 90

4. An improved rolling-mill, consisting of 95 two sets of rolls arranged to rotate in opposite directions, of stationary entering and delivery tables for each set of rolls, said tables being composed of rollers mounted in suitable frames, of means to rotate the rollers of the entering-tables in the direction of their 100 respective rolls, and of means for transferring the article being rolled transversely over the delivery-tables and onto the entering-tables adjoining them, substantially as set forth.

In testimony whereof I have signed this 105 specification in the presence of two subscribing witnesses.

SAMUEL T. WILLIAMS.
